UNITED STATES PATENT OFFICE.

ERNEST F. WIEDERHOLDT, OF ST. LOUIS, MISSOURI.

BOTTLE CRATE OR CONTAINER.

1,317,845.

Specification of Letters Patent.

Patented Oct. 7, 1919.

Application filed December 15, 1917. Serial No. 207,248.

To all whom it may concern:

Be it known that I, ERNEST F. WIEDERHOLDT, a citizen of the United States, residing at St. Louis, Missouri, have invented a certain new and useful Improvement in Bottle Crates or Containers, of which the following is a full, clear, and exact description, such as will enable others skilled in the art to which it appertains to make and use the same.

This invention relates to crates or boxes of the kind that are used for shipping and storing beer and other bottled beverages. The shipping crate or box that is now generally used for bottled goods of the character mentioned consists of a rectangularly shaped box usually made of wood and provided with crossed partitions that divide the interior of the case into twenty-four compartments or pockets in which the bottles are arranged in an upright position. One objection to crates of the kind referred to which has now become a serious matter, due to the shortage of freight cars, the shortage of materials from which the crates are made and the scarcity of labor employed to handle the crates, is that a relatively great percentage of the space in the case or box that forms the inclosing wall of the crate is not utilized. In order to emphasize what this means to a manufacturer of bottled beverages who ships approximately one hundred thousand dozen bottles per day, I desire to point out that it requires fifty thousand crates of the kind now in general use to pack one hundred thousand dozen bottles and requires fifty box cars, each of sixty thousand pounds capacity, for transporting said crates away from the factory at which the beverage is bottled. The same number of crates and the same number of box cars are used each day in returning the empty bottles to the manufacturer. I am aware of the fact that bottle crates or containers have heretofore been devised with a view to increasing the number of bottles that can be stored or packed in a crate of standard dimensions, but owing to the excessive cost, increased weight and impracticable construction of such crates, they have not gone into general use.

The main object of my invention is to provide a practicable bottle crate or container of novel construction which is so designed that it will hold nearly twice as many bottles as a bottle crate of the kind now in general use, thus effecting a great saving in the num-

ber of crates required by a manufacturer of bottled beverages to ship his product and return the empty bottles to the factory, in the number of cars or other conveyances required to transport the crates to and from the factory and also effecting a great saving in freight charges and in the number of operatives required to load the crates onto and off of the conveyances in which they are transported.

Another object is to provide a bottle crate or container having the characteristics above referred to that can be manufactured and sold at a low cost; that is light in weight and which is sufficiently strong and rugged to successfully withstand the rough usage to which it is subjected. Other objects and desirable features of my invention will be hereinafter pointed out.

To this end I have devised a bottle crate or container in which the means that holds the bottles in spaced relation is constructed principally of wire and is so formed that a portion of the bottles in the crate are held in spaced relation in an upright position, and the remainder of the bottles are held in spaced relation in an inverted position between the upright bottles. With crates of the kind referred to a bottler or manufacturer whose product is sold in bottles can ship approximately one hundred thousand dozen bottles per day in approximately thirty thousand crates, and can transport said crates away from his factory in approximately thirty four box cars, each of sixty thousand pounds capacity, thereby effecting a saving in crates of approximately twenty thousand per day and a saving in box cars of approximately sixteen per day.

My improved crate, when empty, weighs substantially the same as the wooden bottle crate now in general use, but in view of the fact that it holds thirty nine bottles instead of only twenty-four bottles, it effects a saving in weight, both in shipping full crates and returning empty crates, of approximately three pounds per dozen bottles. This saving of approximately three pounds per dozen bottles is a large item in freight expense, and at an average freight rate of forty two cents per hundred pounds (N. Y. C. L. rate), effects a saving of approximately \$1,260.00 per day, or \$378,000.00 per year on out-going freight or filled crates and the same amount on inbound freight or empty crates that are returned to the fac-

tory, thus making a total saving on freight charges per year of approximately \$756,000.00. Furthermore, with crates of the kind now in general use it is not possible to load 5 a box car to its full capacity, owing to the fact that one thousand of the ordinary crates containing twenty four thousand full bottles and weighing fifty one thousand pounds fill a box car of sixty thousand pounds capacity. 10 With my improved crate it is possible to overload a box car ten per cent. beyond its rated capacity, a thing that is requested by the Federal Government to relieve the car shortage, owing to the fact approximately 15 eight hundred and eighty three of my crates containing approximately 34,437 bottles and weighing in the neighborhood of sixty thousand pounds can be shipped in a box car of sixty thousand pounds capacity. With the 20 wooden crates of the kind now in general use it is necessary to use approximately fifty cars per day to return crates containing one hundred thousand dozen empty bottles to the factory, whereas, with my improved 25 crate, approximately thirty cars per day are sufficient to return the same number of bottles to the factory. Accordingly, a manufacturer or bottler whose daily output is one hundred thousand dozen bottles, by using 30 my improved crate, is enabled to handle his product with thirty six less freight cars per day than would be required if the ordinary bottle crates were used. Assuming that the manufacturer's plant operates three hundred 35 days in the year, the total number of cars that will be released or not required by the manufacturer to handle his product, is 10,800.

In addition to the great saving that is 40 effected in the number of crates required, in the number of cars, trucks or other conveyances used to transport the crates to and away from the factory and in freight charges, my improved crate reduces the 45 number of operatives required to load the crates onto and off of the conveyances, the saving in the labor item alone being approximately forty per cent.

My complete crate consists of a box or 50 container preferably of rectangular shape, having arranged inside of same a skeleton-like structure formed principally of wire and comprising partition members arranged at right angles to each other and bent into 55 such shape that they form a series of compartments in which bottles can be arranged in an upright position, and a series of compartments in which bottles can be arranged in an inverted position between the upright bottles, the inverted bottles being sustained by ring-shaped members that are connected to said partition members, and being held in a vertical position by the edges 60 of partition portions on said partition members that bear against the caps on the necks 65

of said inverted bottles. Each of the partition members is preferably formed from a single strand of wire that can be shaped quickly and at a low cost in a wire bending machine, and after the partition members 70 and ring-shaped members have been combined or assembled, they are preferably permanently united with each other by dipping the entire structure in a bath of galvanizing solution. After the skeleton-like partition 75 structure has been completely formed, it is arranged in operative position in the box or container that forms the outer wall of the crate. While I have described my complete 80 crate as consisting of a box or container and a skeleton-like partition structure arranged inside of same, I wish it to be understood that the essential feature of my present invention consists in the partition structure, *per se*. Therefore, it is immaterial, so far 85 as my invention is concerned, whether said partition structure is used or sold alone or in combination with a box or container.

Figure 1 of the drawings is a top plan view of my improved bottle crate or container, with the lid or cover of the crate removed.

Fig. 2 is a longitudinal sectional view of said crate.

Fig. 3 is a perspective view of a portion of the partition structure.

Fig. 4 is an enlarged detail view of a portion of said structure, for the purpose of more clearly illustrating the construction of the ring-shaped members that are combined 100 with the partition members; and

Fig. 5 is a perspective view, illustrating a slight modification of my invention.

Referring to Figs. 1 to 4 of the drawings, which illustrate the preferred form of my 105 invention, A designates a box or container, preferably of rectangular shape and constructed of wood or other suitable material, said container being provided with a lid or cover B. Said container is provided with a 110 skeleton-like partition structure that comprises a plurality of partition members C that extend longitudinally of the container A and also a plurality of partition members D that extend transversely of said container. 115 At points where the partition members intersect or cross each other ring-shaped members E are arranged. The partition members C and D are arranged at right angles to each other so that they will form spaces 120 α in which bottles α' can be arranged in an upright position, and the ring-shaped members E form spaces γ into which the necks of inverted bottles γ' can be inserted, as indicated by broken lines in Fig. 2, the body 125 portions of the inverted bottles γ' resting upon the ring-shaped members E and the necks of said inverted bottles being positioned between the body portions of the upright bottles α' . The partition members C 130

and D are formed from wire and each of said partition members is preferably constructed from a single strand of wire that is bent to form a series of vertically-disposed 5 partition portions 1 whose lower ends are connected together by base portions 2, the partition portions 1 of each partition member lying in the same vertical plane. The particular shape or configuration of each 10 partition portion is immaterial, so far as my broad idea is concerned, but the general shape of each partition portion is that of an inverted U, one of whose side legs is bent laterally toward the other side leg so as to 15 form a horizontally-disposed, U-shaped portion 1^a, as shown in Fig. 2. The partition portions 1 are preferably so formed that the edges of same which are presented to the necks of the inverted bottles will contact 20 with the caps on said inverted bottles, and thus hold said inverted bottles in a vertical position, this being effected by making the side legs of the partition portions 1 slightly inclined, as shown in Fig. 4 and also in Fig. 25 2, wherein it will be seen that the cap on the neck of the inverted bottle, indicated in broken lines, bears against the partition portions 1 between which said neck is arranged. The partition members C and D are so arranged 30 that the base portions 2 of same will cross each other, thus causing the partition portions 1 to form the side walls of the pockets x in which the upright bottles are arranged, the base portions 2 of the partition members C being bent upwardly at 2^a and the base portions 2 of the partition members D being bent downwardly at 2^b as indicated in Fig. 3, so as to interlock the partition members C and D with each other at the 35 points where they cross or intersect. I also prefer to provide the end partition portions 1 of the partition members with hooks 3 arranged in such a manner that the hooks 3 at the ends of each of the partition members 40 C will engage the base portions of the transversely-disposed partition members D at the ends of the container, and the hooks 3 at the ends of the transversely-disposed partition members D will engage the base portions of 45 the partition members C that are arranged nearest to the side walls of the container. The ring-shaped members E, previously referred to, can be formed in various ways 50 without departing from the spirit of my invention, but I prefer to form said ring-shaped members in the manner illustrated in Figs. 1 and 3, wherein it will be seen that the ring-shaped members E are joined together in groups, each of which comprises 55 five ring-shaped members that are joined together by connecting portions 4 that extend parallel to the longitudinally-disposed partition members C. Each of the ring-shaped members of each group is also provided with 60 two radially-projecting portions 5 arranged 65 at right angles to the connecting portions 4, which radially-disposed portions 5 are utilized for connecting the ring-shaped members E to the transversely-disposed partition members D. The connecting portions 4 and 70 the radially-disposed portions 5, previously referred to, are of substantially channel shape in cross section so that they can be bent around the top cross pieces of the partition portions 1 of the partition members, thereby 75 securely connecting the partition members together. In making the skeleton-like partition structure of my improved crate the partition members C and D are formed from strands of wire that are first bent into 80 proper shape by means of a wire bending machine, or in any other suitable manner, and said partition members are then arranged in proper position with relation to each other and joined together by the hooks 3 85 and the coöperating crimped portions 2^a and 2^b on the base portions of same and also by bending the channel-shaped portions 4 and 5 of the ring-shaped members E into engagement with the top cross pieces of the partition portions 1 of said partition members. If desired, the entire structure can thereafter be dipped into a galvanizing solution 90 so as to make the entire structure rust-proof and also solder the coöperating parts of 95 same together.

Instead of forming the ring-shaped members in units, each of which comprises a plurality of ring-shaped members that are joined together by integral connecting portions, individual rings E can be used, as 100 shown in Fig. 5, each of which is joined to the top cross pieces of the partition portions 1 with which it coöperates by means of clips 7 that are adapted to be wrapped around 105 said top cross pieces and which are provided at their ends with reduced extensions 7^a that can be wrapped around the rings E'. After the skeleton-like partition structure has been 110 formed in the manner above described, it is thereafter arranged in operative position in the box or container A and either permanently secured to same by fastening devices, or is left free so that it can be removed easily 115 to facilitate the cleaning of the box A.

While I have described my improved crate as consisting of a box or case A and a skeleton-like partition structure formed of wire and arranged inside of said case, I wish it to be understood that the essential feature of 120 my present invention consists in the skeleton-like partition structure that holds the bottles in proper spaced relation. Therefore, it is immaterial whether the skeleton-like partition structure is built and sold with the box A, or is built and sold as a 125 separate unit which can thereafter be arranged by the user in a suitable box or container.

Having thus described my invention, what 130

I claim and desire to secure by Letters Patent, is:

1. A bottle crate or container provided with a partition structure composed of a plurality of right-angularly-disposed wire partition members having parts which cross and interlock with each other at the lower side of the structure, said partition members each comprising a plurality of vertically-disposed partition portions for receiving bottles in an upright position, and substantially ring-shaped members combined with said partition members at points in alinement with the parts of said partition members which cross each other so as to form a series of pockets for receiving inverted bottles that lie between the pockets formed by the vertically-disposed partition portions of said partition members, said vertically-disposed partition members having laterally-projecting loops intermediate the top and bottom portions thereof which act as guides for the upright bottles.
2. A partition structure for bottle crates or containers composed of a plurality of right-angularly-disposed partition members formed from wire and comprising vertically-disposed partition portions and connecting base portions that rest upon the bottom of the container in which the structure is used, the base portions of the partition members that extend in one direction being bent around the base portions of the partition members that extend in the opposite direction, means arranged between the partition portions of said partition members so as to connect said portions together at the top of the structure and also form pockets in which inverted bottles can be arranged, said partition portions forming pockets in which upright bottles can be arranged, and laterally-projecting loops arranged intermediate the top and bottom of said partition members so as to form guides for said upright bottles.
3. A partition structure for bottle crates or containers composed of a plurality of right-angularly-disposed intersecting partition members formed of wire, each of which comprises a series of vertically-disposed partition portions spaced away from each other

and connected together at their lower ends by base portions, the oppositely-disposed base portions of the partition members being bent around and interlocked with each other at the point of intersection, substantially ring-shaped members arranged between said vertically-disposed partition portions, and means for securing said ring-shaped members and said partition portions together so as to reinforce and strengthen the structure.

4. A partition structure for bottle crates or containers composed of a plurality of right-angularly-disposed partition members, each of which is formed from a strand of wire bent to form a plurality of spaced, vertically-disposed partition portions whose lower ends are joined together by base portions, the base portions of the partition members that extend in one direction being bent around the base portions of the partition members that extend in the opposite direction so as to interlock therewith, substantially ring-shaped members arranged between the various partition portions of the structure, and lateral members that extend between said ring-shaped members and which embrace the top cross pieces of said partition portions so as to rigidly connect said partition portions together at the top side of the structure.

5. A partition structure for bottle crates or containers composed of a plurality of intersecting partition members constructed from wire that is bent to form right-angularly-disposed partition portions that cooperate with each other to form open-ended pockets in which upright bottles can be arranged, devices arranged between said partition portions so as to serve as supports for inverted bottles, said partition portions being so constructed that the edges of same which are presented to the necks of the inverted bottles will bear against the side edges of the caps or closures on same and thus hold said inverted bottles in a vertical position, and loops intermediate the top and bottom of some of the partition portions which act as guides in placing the upright bottles in position.

ERNEST F. WIEDERHOLDT.

Copies of this patent may be obtained for five cents each, by addressing the "Commissioner of Patents, Washington, D. C."
